HOLDER FOR POWER TOOTHBRUSH UNIT

Richard B. Hall, Cincinnati, Ohio, assignor to Dominion
Electric Corporation, a corporation of Ohio

Filed Apr. 10, 1964, Ser. No. 79,438

Term of patent 14 years

(Cl. D4—3)

FIG.1

The power unit shown in broken lines in FIGURE 3 is included for illustrative purposes only.

I claim:

The ornamental design for a holder for power toothbrush unit, substantially as shown and described.
